UNITED STATES PATENT OFFICE.

MURRELL C. WARREN AND JULIUS J. KROHN, OF ARCATA, CALIFORNIA, ASSIGNEES
TO CALIFORNIA BARREL CO., OF SAN FRANCISCO, CALIFORNIA, A CORPORATION
OF CALIFORNIA.

DRY KILN.

Application filed November 30, 1921. Serial No. 518,928.

To all whom it may concern:

Be it known that we, MURRELL C. WARREN and JULIUS J. KROHN, citizens of the United States, residing at Arcata, in the county of Humboldt and State of California, have invented certain new and useful Improvements in Dry Kilns, of which the following is a specification.

Our present invention relates to an improvement in dry kilns and in the provision of a kiln adapted for uniformly drying staves, heading, box shooks, lumber or any product by reversing the natural draft or circulation of hot air through the stock during the drying period.

One of the principal objects of this invention is to provide a kiln equipped with an arrangement of grouped heating elements and baffles, so disposed as to enable the circulation of heated air in its direction of travel through the stock to be changed at will by a variation in the temperature of the grouped heating elements or their position relative to the material to be dried, without the aid of artificial draft means. To provide a construction wherein the drying operation is performed by a natural draft of heated air and one which is capable of operating to dry the stock uniformly throughout the charge.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

In the embodiment of the invention illustrated—

Fig. 1 is a transverse sectional view through a progressive kiln, taken on line 1—1 of Fig. 4, illustrating the downward circulation of air through the stock.

Fig. 2 is a view similar to Fig. 1, taken on line 2—2 of Fig. 4, with the circulation of the air upwardly through the stock.

Fig. 3 is a longitudinal sectional view horizontally through the kiln, taken on line

3—3 of Fig. 4, disclosing the grouping of the heating elements.

Fig. 4 is a vertical sectional view taken on line 4—4 of Fig. 3, disclosing the connection for the grouped heating elements.

In the drawings, wherein like characters of reference designate corresponding parts— 60 1 indicates the kiln housing preferably rectangular in plan and longitudinally through which extend tracks 2 raised or elevated from the bottom 3 thereof and supported preferably on girders 4 resting on 65 piers 5. The tracks 2 extend from the kiln charge end 6 in pairs longitudinally through the same to the discharge end 7, and the openings 8 in opposite ends of the kiln through which said tracks extend are adapt- 70 ed to be closed by doors or other suitable mechanism, not shown, to provide a closing chamber within the kiln housing 1.

Transversely across the bottom of the housing 1 below tracks 2 and positioned about midway of the length of the housing is a suitable outlet duct 9, which communicates with a vertical portion or outlet stack 10. Extending longitudinally within the kiln and one paralleling the outer edge of 80 each track 2 are the baffles 11, each extending from the bottom 3 of the housing to a point slightly above the upper edge of the tracks 2.

It will be observed in Figs. 1 and 2 that the baffles 11 parallel each pair of tracks 2 85 at their outer sides and provide walls for separating adjacent pairs of tracks providing between them flues 12. The baffles for substantially their full length are provided at their lower edges with vents 13 which connect the base of flues 12 with the chambers 14 formed by the baffles beneath each pair of tracks 2.

Grouped in the flues 12 between adjacent pairs of tracks 2 at the charge end of the 95 kiln and extending preferably to a point slightly beyond the duct 9 are the heating elements 15 preferably in the form of steam pipes connected with a header 16 and draining into a drain 17 connected with a trap 100 18. The pipes 15 are adapted to cause a circulation of air upwardly through the flues 12 between the charges of material 16' on tracks 2 at the charge end of the kiln and cause the same to circulate down- 105 wardly through the stock into the unoccu-

pied chamber 14 beneath each pair of rails, maintaining this circulation through the vents 13 solely by the temperature of said grouped pipes 15. This downward circulation of heated air through the stock, when the same is fed green into the charge end of the kiln, takes advantage of the natural tendency of air on cooling to descend and thus create a definite circulation in the direction of the arrows A, Fig. 1, without mechanical stimulation. This operation thoroughly heats the material and slowly dries out the free moisture contained within the cells.

15 Between the pairs of rails 2 and cooperating pairs of baffles 11 in the chambers 14 are grouped other heating pipes 18, preferably supplied with steam from the header 19 and which drain into a member 20 connected with a trap 21, and said pipes are of a length extending approximately one-half the length of the housing 1 and as will be observed by a comparison of Figs. 1 and 2 are of a greater number per unit or group 20 than those positioned within the flues 15, thereby creating a greater temperature at the discharge end of the kiln than at the charge or receiving end.

30 The stock as it progresses through the kiln moves over the groups of pipes 18 where it is subjected to a rising circulation of heated air passing upwardly from the chambers 14 through the stock in the direction of the arrows B—Fig. 2 of the drawings, the intense rising heat moving by natural draft circulation upwardly through the chambers 14, stacks 16 and downwardly through flues 12 and inwardly through vents 13 encounters little resistance in passing 35 through the stocks, as the greater percentage of moisture has been removed from the material in the early stages of drying.

40 By this present apparatus, which has

been illustrated in connection with a progressive kiln, but which is equally as well 45 adapted for use in a compartment kiln, the stock is uniformly dried by alternate natural circulation of heated air controlled solely by or the position of the stock relatively to certain groups of heating elements.

50 Fresh air is adapted to be admitted at opposite sides of the kiln for its full length between the kiln supporting members 1.

We claim:

1. A dry kiln including a housing for receiving the material to be dried, a plurality of grouped heating elements below the plane of the material, one group lying directly beneath the material and the other group lying on either side of the material, and a 60 pair of vented baffles for controlling circulation of heated air through said material.

2. A progressive kiln comprising a housing, means for directing the material to be dried therethrough, a group of heating elements lying beneath the material at one point of its travel through the housing, a group of heating elements below the material on either side at another point of its travel through the housing, and a pair of vented 70 baffles at each side of the material between the planes of the groups of heating elements throughout the length of the kiln.

3. A kiln comprising a housing for receiving the material to be dried, a plurality 75 of groups of independent heating elements lying beneath the material at its point within the housing and on either side thereof, and a pair of vented baffles at each side of the material between the planes of the 80 groups of heating elements.

In testimony whereof we have signed our names to this specification.

MURRELL C. WARREN.
JULIUS J. KROHN.
